UNITED STATES PATENT OFFICE.

CHARLES E. WILLIAMS, OF CHICAGO, ILLINOIS.

AUDIPHONE-TRANSMITTER STAND AND SOUNDING-BOARD.

1,125,424.

Specification of Letters Patent.

Patented Jan. 19, 1915.

Application filed January 14, 1911. Serial No. 302,600.

To all whom it may concern:

Be it known that I, CHARLES E. WILLIAMS, a citizen of the United States, residing at the city of Chicago, in the county of Cook and State of Illinois, have invented a new and useful Improvement in Audiphone-Transmitter Stands and Sounding-Boards, of which the following is a specification.

10 My invention relates to the practical application of external hearing devices of a class described in my U. S. Patent No. 911,101, issued to me February 6, 1909. For carrying on an ordinary conversation, when a small number of people are near together, it is sufficient if the receiver is concealed in the clothing or exposed by laying it in any convenient place. But in a larger company, where a general conversation is 20 carried on, as around a dining table, in consultations and the like, and where voices vary greatly in force, tone, pitch and expression, it is desirable to place the instrument in the open to intensify the sounds 25 which are to be transmitted and to free it from any deadening of the vibrations which may be caused by a solid support with which it may be in contact.

It is the object of my present invention to 30 provide a stand by which one or more of such transmitters may be intercepted and communicated thereto with the greatest freedom, which will amplify the sounds so communicated, and by which any deadening 35 effect of a non-vibratory support may be overcome. By its particular conformation it is adapted to receive at a proper angle sound waves coming to it from almost any direction. And it is especially adapted to 40 hold receivers of the class set out in said patent at the best working angle of inclination thereof.

The principles of my invention are illustrated in the drawings, in which— 45 Figure 1 shows a perspective view of my invention showing two separate hearing devices attached thereto; Fig. 2 is a rear view thereof; Fig. 3 is a vertical section of Fig. 2 on the line 3—3; Figs. 4 and 5 show modifications of the device.

Further describing my invention with reference to the drawings, 1 in Fig. 3 shows a body portion, preferably of metal, having a depressed part 2 adapted to form an electrode chamber 2'. Within said chamber is secured the button electrode 3 while form-

ing the other side of said chamber, and providing the other electrode is the diaphragm 4. A closed reverberatory chamber 5 is formed by the casing 6 secured to the frame 60 piece 1 with its edges adjacent to the periphery thereof.

7 is a protecting casing for the rear of the instrument secured thereto by the screw 8, which takes the bridge 9. The said transmitter is mounted upon a support 10. The latter consists of a sheet of resilient material of comparatively large size, preferably of hard rubber, to which should be given a number of folds so as to reduce the extent thereof, and confine it to moderate dimensions in the form shown in Fig. 1. There is a base portion 11, a standard portion 12, and a free member 13. The latter is given an upward fold 14 at its extremity, 75 whereby is formed a pocket in which a receiver 15 may be conveniently placed. The base portion may be provided with a reinforcement 16 and the whole should be placed upon cushioning feet 17, which may be 80 of soft rubber. The effect of the said feet is to free the instrument from the deadening effect of a heavy non-vibrating table or other support upon which it may be placed and also to allow the said lower 85 portion to act freely as a sounding board. A similar effect may be produced as shown in Fig. 4 by suspending the device by means of a spring 18 as shown in Fig. 4.

The device shown in Fig. 1 is provided with two receivers A and B. In order that the same may be suitably mounted the members 12 and 13 are provided with circular openings corresponding substantially to the external diameter of the electrode chamber. 95 On removing the casing 9 said chamber is placed in the opening and when the casing is replaced the transmitter will be securely fastened to the support and become practically a part thereof. As indicated the 100 transmitter A has the front portion of the same outside the device. The transmitter B is secured within the device and with the front portion to the rear. The small openings 20 in the member opposite each transmitter tend to aid the passage of sound waves, but do not interfere in any way with the vibratory action of the apparatus. The transmitter shown which is in substance that in my patent first above referred to, 110 shows a carbon button electrode having pockets in which are small carbon globes

or particles which contact with the diaphragm, the instrument works to best advantage when so inclined that said particles gravitate toward the diaphragm. And the upper walls of sectors of this support or sounding board should be so slanted as to give the instrument the proper inclination. It will be seen that the transmitters may be connected by suitable electric wiring which will be familiar to every one, so as to act in unison, while they may be used separately if desired. In any event the support is completely free to act as a sounding board to receive and amplify the vibrations which are received and cause them to act with the greatest fullness and effect in modifying the electrical waves which are transmitted to the receiver. The form of the sounding board adapts it to receive sound waves from all directions, whereupon they are distributed to all the transmitters. The device shown in Fig. 5 indicates a method of construction by which a large number of transmitters may be secured together within a very small compass.

I claim:

1. A support for audiphone transmitters comprising a base, a vibratory member mounted thereon, and a vibratory plate for carrying the transmitter supported by the vibratory member.
2. A support for audiphone transmitters comprising a base, a vibratory member mounted thereon, and a plate for carrying the transmitter supported by the vibratory member, such plate having a free edge.
3. A support for audiphone transmitters comprising a base, a vibratory member mounted thereon, and a plate for carrying the transmitter, attached at one edge to the vibratory member and being otherwise free.
4. A supporting device and sounding board for audiphone transmitters, consisting of a base portion, and a transmitter sup-

port on said base comprising a plurality of resilient plates having angular connection with each other, one of said plates having a free edge and the other being secured to the base portion.

5. A supporting device and sounding board of audiphone transmitters, consisting of a base portion, cushioning supporting means therefor, and a transmitter support on said base comprising a plurality of resilient plates having angular connection with each other, one of said plates having a free edge and the other being secured to the base portion.

6. A support for audiphone transmitters consisting of a sounding board having a supporting portion and a plurality of corresponding vibratory portions disposed in angular relation to each other and the supporting portion.

7. In a sound-transmitting device, in combination, a sounding board comprising two leaves united at their upper edges and each being inclined from the vertical, and an audiphone transmitter mounted on each leaf.

8. A supporting device and sounding board for audiphone transmitters, consisting of a base portion, cushioning supporting means therefor, and a transmitter support on said base comprising a plurality of resilient plates having angular connection with each other, one of said plates having a free edge provided with an upwardly turned portion, and the other being secured to the base portion.

In witness whereof, I have hereunto set my hand, this 7th day of January A. D. 1911, in the presence of two subscribing witnesses.

CHARLES E. WILLIAMS.
